(57) **CLAIM**

The ornamental design for a locket with removable pendant holder, as shown and described.

DESCRIPTION

FIG. 1 is a perspective view of a locket with removable pendant holder showing my new design;

FIG. 2 is a right side view thereof;

FIG. 3 is a left side view thereof;

FIG. 4 is a bottom view thereof;

FIG. 5 is a top view thereof;

FIG. 6 is a front view thereof;

FIG. 7 is a rear view thereof; and,

FIG. 8 is a perspective view thereof with the pendant holder shown detached.

The broken lines shown in the drawings illustrate portions of the locket with removable pendant holder that form no part of the claimed design.

1 Claim, 6 Drawing Sheets
